UNITED STATES PATENT OFFICE

143,558

DESIGN FOR AN INFUSION UNIT FOR A COFFEE MAKER

Roland L. Smith, Belmont, Mass., assignor to Nu-
products Corporation, Cambridge, Mass., a cor-
poration of Massachusetts

Application June 12, 1945, Serial No. 120,038

Term of patent 14 years

(Cl. D44—26)

To all whom it may concern:

Be it known that I, Roland L. Smith, a citizen of the United States of America, residing at 11 Chester Road, Belmont, in the county of Middlesex and State of Massachusetts, have invented a new, original, and ornamental Design for an Infusion Unit for a Coffee Maker, of which the following is a specification, reference being had to the accompanying drawing, forming part thereof.

The unit is circular in cross section throughout its height.

The single figure of the drawing is a side elevational view of an infusion unit for a coffee maker showing my new design.

I claim:

The ornamental design for an infusion unit for a coffee maker, as shown and described.

ROLAND L. SMITH.
